UNITED STATES PATENT OFFICE

JAMES N. WYANT, OF AKRON, OHIO

DESIGN FOR A TIRE

Application filed June 10, 1932. Serial No. 44,051. Term of patent 14 years.

To all whom it may concern:

Be it known that I, JAMES N. WYANT, a citizen of United States, residing at Akron, in the county of Summit and State of Ohio, have invented a new, original, and ornamental Design for a Tire, of which the following is a specification, reference being had to the accompanying drawing, forming part

Fig. 1 is a perspective view of a tire showing my new design;

Fig. 2 is a fragmentary side elevation, on a larger scale;

Fig. 3 is a cross-sectional view taken on line III—III of Fig. 2; and

Fig. 4 is a fragmentary cross-sectional view taken on line IV—IV of Fig. 2.

I claim:

The ornamental design for a tire, as shown.

JAMES N. WYANT.
